CLAIM

The ornamental design for a cart, as shown and described.

DESCRIPTION

FIG. 1 is a front perspective view of a cart showing my new design, and

FIG. 2 is a back perspective view thereof,

FIG. 3 is an enlarged fragmentary plan view of a portion of one of the shelves of the cart, it being understood that the apertures shown therein are repeated uniformly throughout the surface of the shelf and that the pattern of apertures in all shelves of the cart are the same.

The pattern of black dots on the surface of the shelves of the cart shown in FIGS. 1 and 2 is understood to represent apertures as best illustrated in the enlarged fragmentary plan view of FIG. 3 showing a portion of a typical shelf of the cart.
